OVERCASTING SEWING MACHINE

Anthony Sardu, Brooklyn, N. Y.

Application October 2, 1943, Serial No. 504,787

1 Claim. (Cl. 112—172)

1

This invention relates to an overcast sewing machine having a needle in the form of a single circular arc and which passes completely through the fabric being stitched.

An object of this invention is to provide improved means for positively holding and driving the needle, the said means comprising a plurality of cavities of circular cross-section in one side of the needle and spring-pressed pins slidably mounted in a rotatable disk or head and adapted to enter said cavities for gripping and rotating said needle.

Another object of this invention is to provide a needle shaft having the said head at one end thereof, and a housing enclosing the head. The head has a circular groove of a depth adapted to receive the needle to approximately one-half of its thickness. A cover has a circular groove for receiving the other half of the needle; means is also provided for securing the cover and housing to the frame of the sewing machine in a manner as to cause concentric alinement of the grooves and for supporting the needle in concentric relation with the needle shaft for rotation thereby.

Another object of this invention is to provide a needle-plate positioned in parallel relation with the needle shaft and having a tongue projecting therefrom and to remove a portion of the housing to permit the tongue to be positioned inwardly of the housing, clear of the path of the needle, and the needle to pass around the tongue.

Another object of this invention is to provide a housing cover having a cut-out portion in alinement with the cut-out portion in the housing and to provide a needle plate positioned in a horizontal plane and adapted for supporting fabric in position for the needle to pass through an edge thereof, the cut-out portion of said cover forming a guide for the fabric.

Another object of this invention is to provide cam means positioned inside said housing and adapted to release said pins successively from said needle prior to the approach of its sharp pointed end to the needle plate to permit successive portions of said needle to pass through said fabric while being rotated.

Another object of this invention is to provide four-motion feeding means in coacting relation with said needle actuating mechanism to cause simultaneous overcast stitching and feeding.

With the above and other objects in view, the invention will be hereinafter more particularly described, and the combination and arrangement of parts will be shown in the accompanying draw-

2

ings and pointed out in the claim which forms part of this specification.

Reference will now be had to the drawings, wherein like numerals of reference designate corresponding parts throughout the several views, in which:

Figure 1 is a side elevation of the sewing machine, partly broken away to show the interior thereof.

10 Figure 2 is an end view showing the front portion of the sewing machine shown in Figure 1.

Figure 3 is a cross-sectional view, the section being taken as on line 3—3 in Figure 8.

Figure 4 is a front elevation of the needle.

15 Figure 5 is a fragmentary perspective view showing a schematic cam and needle-gripping pin arrangement.

Figure 6 is a fragmentary top plan view of the cam and needle gripping pins.

20 Figure 7 is a front view of the housing and head or carrier for the needle-gripping pins.

Figure 8 is a front view of the housing and threading door, on an enlarged scale.

25 Figure 9 is a plan view of the cloth and needle plates, and a stitched fabric strip.

Figure 10 is a plan view of four-motion actuating mechanism for the feed-dogs.

30 Figure 11 is a side elevation of the feeding mechanism shown in Figure 10.

Figure 12 is a fragmentary cross-sectional view of the mechanism shown in Figures 10 and 11, the section being taken as on line 12—12 in Figure 11.

In the illustrated embodiment of the invention, the numeral 10 indicates a sewing machine comprising a fixed hollow box-like frame 11 having a main drive-shaft 12 mounted in the lower portion thereof, the drive-shaft 12 having a gear 13 secured thereon.

40 An idler shaft 14 is rotatably mounted in the frame 11 above the shaft 12 and carries a gear 15 which is in intermeshing relation with the gear 13.

45 A needle shaft 16 is rotatably mounted in a housing 17 at the front end of the frame 11. The needle shaft 16 is in right-angular relation with the idler shaft 14.

50 A bevel gear 18 secured to the idler shaft 14 is in intermeshing relation with a bevel gear 19 secured to the needle shaft 16. The housing 17 is secured to the frame 11 by screws 20. One end of the housing 17 has a circular portion 21. A cover 22 having a circular portion 23 of the same periphery as the circular portion 21 of the housing 17 is secured to the housing 17 by screws 24.

55 As shown on an enlarged scale in Figure 3,

the arcuate needle 25 is rotatably mounted in a circular groove 26 in a disk-shaped enlargement 27 at one end of the needle shaft 16. The disk-shaped enlargement 27 is enclosed by the hollow circular portion 21 of the housing 17. It will be noted that the needle 25 is also rotatably mounted in a circular groove 28 in the circular portion 23 of the cover 22.

It is to be noted that the needle 25 has cavities 30 positioned crosswise of the needle and that shoulder pins 31 having pointed ends 32 slidably mounted in the disk-shaped portion 27 of the needle shaft 16, are resiliently pressed by coil springs 33 into the cavities 30 and into engagement with the needle 25.

For the purpose of this invention, the shoulder pins 31 must be released successively from engagement with the needle 25 prior to the approach of the sharp pointed end 32 of the needle to a cloth plate 49 having a horizontally positioned work supporting surface. I provide an arcuate cam 41 fixed to the end wall 42 of the housing 17. The cam 41 has a sharp end 43 which successively engages collar-shaped outer ends 38 of the pins 31 and pulls the pins in a direction parallel with the shaft 16.

Each shoulder pin 31 and spring 33 is mounted inside an aperture 34 in the disk-shaped portion 27 of the needle shaft 16. I provide apertured disks 35, Figure 6, which are suitably mounted in the reduced end portions 36 of the pins 31. Rivets 37 hold the disks 35 fixed to the outer surface of the disk-shaped portion 27. In the assembled position shown in Figure 6, the disk-shaped outer end 38 of the shoulder pin 31 is in spaced relation from the vertical face 44 of the disk-shaped portion 27 a distance sufficient to cause disengagement of the pins 31, one at a time, from the needle 25, prior to the approach of the needle cavities 30, 30, to the cloth plate or work supporting base 40.

It is to be noted that the spaced relation of the collar-shaped outer ends 38 of the shoulder pins 31 from the rear face 44 of the disk-shaped portion 27 is such as to permit each collar 38 to engage the sharp end 43 of the stationary cam 41. When the collar 38 reaches the mid-portion of the cam, the pin 31 is pulled out of engagement with the needle. During the time the collar remains in contact with the cam, the pin remains out of engagement with the needle. The moment the collar passes the cam, the pin is instantly forced back into engagement with the needle by the spring 33.

In the embodiment of the device shown in Figures 4 to 7 inclusive, the needle 25 used therewith has two cavities 30 for engagement with two pins 31. Under practical conditions where heavy material is to be penetrated by the needle, three cavities 30 and three pins 31 may be employed so as to provide two pins in engagement with the needle while one pin is out of engagement.

As shown in Figure 8, the annular cover 23 on the housing 17 (Figure 3) has a threading door 45 pivotally mounted on a pin 46 secured in ears 47 integral with the housing cover 22. The door 45 has a threading aperture 48 therethrough. The aperture 48 is positioned in the axis of rotation of the needle 25 to permit a thread passing through the aperture into the opening within the annular cover 23 to follow the needle during its rotation.

It is to be noted that the needle thread is at the central portion of the axis of the orbit of the needle and that an end of the thread is threaded

in the needle. The length of thread from the aperture 48 to the needle is thus constrained to follow the orbit of a cone.

An embodiment of a four-motion double feeding mechanism 50 is shown at one end of the machine in Figure 2. The feeding mechanism 50, best shown in Figures 10 to 12 inclusive, comprises a front feed-dog 51 and a rear feed-dog 52.

The feed-dogs 51 and 52 are respectively carried by elongated feed bars 53 and 54 which are positioned in parallel relation and extend from the front to the rear of the machine. The feed bar 53 adjoins an end face of the frame 11.

At the rear, each feed bar is bifurcated to provide rectangular openings, the opening in the bar 53 being numbered 55 and the opening in the bar 54 being numbered 56. The openings 55 and 56 receive in sliding engagement a rectangular block 57, which is rockably mounted upon a pin 58 fixed in the frame 11.

At the front, each feed bar is bifurcated to provide rectangular openings, the opening in the bar 53 being numbered 60 and the opening in the bar 54 being numbered 61. The openings 60 and 61 receive in sliding engagement a rectangular block 62 which is mounted on an eccentric portion 63 of the shaft 12 and is vertically movable to lift the feed-dogs.

At the end adjacent the eccentric portion 63, the main shaft 12 has a reduced stem 65 which is concentric with said shaft. Upon the concentric stem 65 there are mounted two eccentrics 66 and 67 keyed to the stem by a key 68.

The eccentrics 66 and 67 impart horizontal motions to the feed-bars 53 and 54, motion being transmitted through a link connection 69 between the eccentric 66 and the feed-bar 54, and a link connection 70 at one side of the link 69, between the eccentric 67 and the feed-bar 53. The forward ends of the links 69 and 70 encircle their respective eccentrics 66 and 67, and at the rear ends are pivotally secured to their respective feed-bars by bolts 71 and 72 which extend from the feed-bars parallel with the shaft 12.

The bolts 71 and 72 serve to clamp sleeves 73 74 against the feed-bars. The sleeves form pivotal supports for the rear ends of the links 69, 70. The link 70 has an elongated opening 75 through which the bolt 72 and sleeve 74 pass without interfering with the movements of the link 69.

In operation, the eccentrics 66 and 67 impart horizontal motions to the feed-dogs 51, 52. The eccentrically actuated block 62 effects vertical movements to the feed-dogs.

Two cooperating four-motion feeding means are thus provided, each of which may operate in all its movements independently of the other. By giving the rear feed-dog 52 a greater amount of horizontal movement a stretching of the fabric may be effected. By giving the forward feed-dog 51 a greater amount of horizontal movement a gathering of the fabric may be effected. The feed-dog 51 operates in advance of the needle 25 and the feed-dog 52 operates in the rear of the needle.

A presser-foot 80 is carried by a presser-bar 81 which is slidably supported in the sewing machine head 82.

In operation, a thread 83 is passed between thread tension discs 84 and then through the threading aperture 48 in the threading door 45. The thread then enters an aperture 85 in the needle 25, then passes through a concealed arcuate

groove 86 in the interior of the needle and finally emerges through an aperture 87 near the pointed end 29 of the needle.

Upon rotation of the pulley 89 the needle 25 is rotated. The needle carries the thread 83 through an edge portion of fabric 90 lying horizontally upon the cloth plate 40. The needle then passes round a tongue 77 in the needle plate 78. Repeated actuation of the sewing machine causes the feed-dogs 51 and 52 to impart a feeding movement to the fabric for every stitch and, as best shown in Figure 9, there is formed a continuous row of overcast stitching 91 along an edge of the fabric 90.

As shown in dotted lines in Figure 2, the upper portion of the presser-bar 81 has a reduced portion 92 which carries a coil spring 93. The upper end of the spring is housed in a cavity in the lower portion of a tubular threaded member 94. The lower portion of the spring 93 rests upon an enlarged lower portion of the presser-bar 81. The threaded member 94 may be adjusted to cause the presser-foot 80 to bear upon the fabric lying upon the cloth plate 40 with a desired feeding pressure. A lifting lever 95 is slidably mounted at the rear of the head 82 and carries a screw 96 by means of which the lever is secured to the presser-bar 81. The operator raises the lever, and presser-bar, and presser-foot to permit the manipulation of the fabric lying between the presser-foot and the needle plate 78.

As shown in Figure 1, this machine comprises a controllable lubricating system 97 shown in my Patent No. 2,202,817. This system comprises wicks 98 lying in an oil reservoir 99 and extending to parts to be lubricated, such as the gears 13, 15 and bearing for the shaft 14, etc. An oil drain valve 100, disclosed in my said patent, maintains a predetermined oil pressure in the oil reservoir. An oil storage chamber 101 and a pump (not shown) serve to provide a constant circulation of oil during operation of the sewing machine.

As shown in Figure 2, the lower portion of the head 82 is broken away to show the presser-bar 81 having a key 102 which is slidably mounted in a slot 103 in a bushing 104. The slot 103 terminates in a circular cavity 105 above the slot. The operator may thus raise the foot 80 so that the

key 102 enters the cavity 105, when it is possible to swing the presser-foot 80 towards the rear or to the left of the machine to provide a clear space in front of the threading door 45.

As shown in Figure 9, it will be seen that the stitching 91 is straight on the top of the fabric, while the stitching below the fabric is inclined. It is to be noted that when it is desired to make inclined stitching on the top or normally exposed surface of the fabric, that the said surface is placed up side down on the cloth plate 40. It is thus possible to stitch straight stitching or inclined stitching as desired on any surface of the cloth.

In accordance with the patent statutes I have described and illustrated the preferred embodiment of my invention, but it will be understood that various changes and modifications can be made therein without departing from the spirit of the invention as defined by the appended claim.

I claim:

In a sewing machine having a stationary frame, a needle shaft, a horizontally positioned work supporting base fixed to said frame and in line with the axis of said needle shaft, a rotatable needle in the form of a semi-circular arc and having a threading passageway in a portion of its arcuate body, and an opening at each end of said passageway, permitting passage of a thread through said passageway, means for causing rotation of said needle, a needle plate positioned parallel with said needle shaft and having a tongue projecting therefrom, said needle being movable between said tongue and the body of said needle plate, said needle plate being adapted to support fabric thereon in a horizontal position, resiliently contacting thread tension disks mounted above said work supporting base, a stationary threading door mounted on said frame in spaced relation from said needle and in parallel relation with the plane of rotation of said needle, said door having a threading aperture in alignment with the axis of said needle, said axially aligned door aperture permitting a continuous supply of thread to be fed to said needle in a conical orbit during rotation of said needle.

ANTHONY SARDU.
